A machine for cutting notches of V cross section in corrugated board. Plural spaced conveyor belts convey the corrugated board beneath a pair of transverse bridges which support cutter assemblies, each of which is transversely movable on its bridge. The cutter assemblies are vertically adjustable, and each includes a vertical plate and a pair of plates inclined at 45° to the horizontal extending perpendicularly to the vertical plate. Each inclined plate supports an electric motor, and has an aperture, the motor shaft extending through the aperture and carrying a cutter. The cutters cooperate to sever a longitudinally extending portion from a corrugated board carried by the conveyor belts, to provide a V-notch in the board.

FIG. 5

V-NOTCHING MACHINE FOR CORRUGATED BOARD

BACKGROUND OF THE INVENTION

The present invention relates to a machine for cutting V-shaped notches in corrugated board being conveyed through the machine.

Containers for shipping and storing merchandise of various kinds have long been made of material which may be generically designated as paper. The earliest such containers were made of paper board, being a single layer of material made from the depositing of cellulosic fibers from an aqueous slurry thereof onto a foraminous support. Later, there was developed corrugated board, in its earliest form being made up of three paper sheets, consisting of an inner corrugated paper sheet and a pair of outer planar liners adhesively secured to the inner corrugated sheet or medium by adhesive applied to the tips of the corrugations. Subsequently, corrugated board was developed including first two corrugated mediums interspersed between three planar liners, and then three corrugated mediums interspersed between four liners. As will be apparent, the strength of these materials was increased, with each successive development, and the containers made therefrom were consequently successively stronger. That is, corrugated board with a single corrugated medium was stronger than paper board, and the double wall board and triple wall board, with two and three corrugated mediums, respectively, were each stronger than single wall board, having but one corrugated medium. These relationships of comparative strength are based upon comparable liner weights and the like, as used in the paper board industry, it being recognized that it might be possible to construct a triple wall board having lesser strength than a single wall board in certain rare instances.

In the making of boxes, the board must be folded from its planar state so as to have, in a conventional box, four walls, each wall being at right angles to the two walls adjacent to it. In order to accomplish this folding, a common practice has been to simply crush the material along a desired line, in a typical regular slotted carton having a stitching flap on one side to provide four parallel score lines. These score lines are the lines along which the board is crushed, to permit the necessary folding. The provision of score lines is a standard practice in the box industry, and has been found to be satisfactory in connection with paper board and single wall and double wall corrugated board. However, it has been found that for triple wall corrugated board, including three corrugated mediums, crushing to provide a fold line has not been satisfactory because of the bulk of material which is compressed at the fold line.

It is known to provide a notch in board material, in order to permit it to be folded, and a number of machines have been proposed to provide one or more V-notches in board which is to be folded into a box or container. For example, in U.S. Pat. No. 442,738, "Knife for Cutting and Scoring Pasteboard" there was provided a conveyor with a transverse bridge or support above it, and a V-shaped knife adjustably supported on a carrier, which in turn could be moved into a selected transverse position on the transverse bridge. Such a construction appeared to be suitable for so-called "pasteboard" but would not be satisfactory for

heavier material, such as triple wall corrugated board.

It has also been suggested, in a generally similar machine, to provide rotary knives carried on adjustable holders, as disclosed in U.S. Pat. No. 362,179 "Apparatus for Grooving Card Board." A generally similar disclosure is contained in U.S. Pat. No. 1,940,106, "Means for and Method of Making Grooved Fibrous Board." These prior art disclosures all were for generally light work, as compared to the cutting of V-notches in triple wall corrugated board, requiring an anvil below the cutters, and not having any means for energizing the cutters, or causing the rotary knives to rotate, other than the movement of the board itself.

In some instances, the provision of V-notches 15 through the use of powered rotary cutters have been proposed. In U.S. Pat. No. 175,892, plural rotary cutters were provided for cutting a V-notch in a wood board, in order to make a wood gutter, the rotary cutters being carried on shafts which were held by fixed 20 supports, the shafts being belt driven from a common power shaft. This arrangement did not provide for any adjustment of the rotary knives, either transversely or vertically. In another suggestion, found in U.S. Pat. No. 2,335,767, a V-notch was obtained in siding for the 25 construction industry in a machine having a pair of posts from each of which extended a transverse arm which was above the conveying means for the siding. Each arm carried a bracket in which was mounted an electric motor, with its axis inclined, provision being 30 made for adjustment of the angle of the motor. On each motor shaft was mounted a rotary saw, and the two saws cooperated together to cut a V-notch in the siding. This construction required the separate adjustment 35 of each of the motors with its rotary saw, as to the angle of inclination, its position along the transverse arm, and also required vertical adjustment of the transverse arm on its supporting post in order to provide for vertical adjustment of the position of the rotary saw or cutter. Thus, this arrangement required a substantial amount 40 of time in order to set up and adjust each motor and its rotary saw separately. Further, this construction did not lend itself to an apparatus in which a plurality of parallel V-notches were to be made by a plurality of saw pairs.

SUMMARY OF THE INVENTION

The present invention is directed to a machine for cutting a plurality of notches of V-cross section in triple wall corrugated board, which is both strong and stiff. 50 The machine includes a conveying system for conveying the board along a horizontal path: the conveying system includes a pair of spaced shafts each provided with a plurality of relatively small width pulleys, with a plurality of conveyor belts, parallel to each other, with each conveyor belt trained on a pair of pulleys. A pair of bridges extend over the conveyor belts each including an upper and a lower transverse rod. On each bridge there are two cutter assemblies: collars on the transverse rods permit transverse adjustment of the cutter assemblies. The cutter assemblies each includes 55 first and second plates which diverge from a common junction at 90° to each other, each plate being at an angle of 45° to the horizontal. An electric motor is supported on each of these plates, and has the shaft thereof extending through an aperture in the plate, there being a rotary saw carried by the shaft. Thus, the two rotary saws are at substantially 90° to each other. The inclined

first and second plates are secured to a vertical plate, the vertical plate being provided with collars which encircle vertically extending guide rods. Vertical adjustment of the vertical plate and the entire cutter assembly, as a unit, is achieved through a screw threaded rod 5 engaging a nut fixed to the vertical plate.

Among the objects of the present invention are the provision of an apparatus for cutting V-notches in heavy duty corrugated board, to provide such an apparatus which will hold rotary cutters in a firm manner so as to achieve accurate notches, and to provide plural rotating, motor driven cutters on a common support. A further object of the present invention is the provision of a V-notching machine providing for ease of adjustment of rotary cutters, as a unit, both vertically and laterally. Yet another object of the present invention is to provide a V-notching machine utilizing plural belts, and not requiring an anvil beneath the rotary cutters.

Other objects and the attendant advantages of the present machine will be readily understood from the following description and the drawings appended hereto.

BRIEF DESCRIPTION OF THE DRAWING

FIG. 1 is a plan view, with portions removed, of a machine in accordance with the present invention.

FIG. 2 is an end elevation of the machine of FIG. 1.

FIG. 3 is a cross sectional view taken on the line 3—3 of FIG. 2.

FIG. 4 is a view taken on the line 4—4 of FIG. 3.

FIG. 5 is a cross sectional view of corrugated board having a V-notch cut by the machine of FIGS. 1—4.

DESCRIPTION OF THE PREFERRED EMBODIMENT

Referring now to the drawings, wherein like or corresponding reference numerals are used for like or corresponding parts throughout the several views, there is shown in FIGS. 1 and 2 a V-notching machine 10 in accordance with the present invention. The machine 10, as shown in FIG. 2, includes supporting legs 11 and 12, which support the frame 13 shown in FIG. 1. The frame 13 supports a first shaft 14 and a second shaft 16, both shafts having a plurality of spaced pulleys thereon. For example, there is shown pulleys 14a . . . 14d on the shaft 14 and pulleys 16a . . . 16d on the shaft 16. The axial length of each pulley is in the order of three inches, and the overall width of the machine is in the order of nine feet, for a machine constructed in accordance with the invention. The pulleys 14a, 16a have a diameter of approximately 6 1/2 inches, and are crown pulleys, to provide adequate belt guidance. A plurality of belts 17 are provided, each belt being trained over a pair of the pulleys. Shaft 16 is driven from motor drive 20 (FIG. 2) through gear 18. The motor drive 20 is controlled by a control panel 19 which includes known, conventional control devices which control all of the electric motors included in the apparatus 10. Completing the conveying apparatus are a pair of idler rolls 21 and 22 which are carried by the frame 13 and extend transversely of the belts 17, from side to side of the machine 10. These idler rolls serve to hold the corrugated board down, against the belts 17.

A pair of supports in the form of bridges 25 and 26, which are substantially identical, extend above and transversely across the conveyor formed by the belts 17. As seen in FIG. 2, the bridge 25 includes a beam 27,

an upper rod 28 of cylindrical cross section and a lower rod 29 of cylindrical cross section, the beam and rods all being parallel and horizontal, and being above the conveyor. Mounted on each of the bridges of the apparatus 10 are a pair of substantially identical supports 30. The supports 30 may be moved transversely on the bridges, and positioned in selected transverse positions on the bridges.

Referring now to FIGS. 3 and 4, there may be seen the rods 28 and 29. On the rod 28 are a pair of collars 31 and 32, connected by a transverse connector member 33. Similarly, slideable on the rod 29 are a pair of lower collars 34 and 36, with a connector member 37 therebetween. A pair of vertical connectors 38 and 39 serve to connect the collars 31 and 34, and 32 and 36, respectively. There is thereby provided a frame, and supported by this frame are a pair of vertical guide rods 41 and 42. The connector member 33 carries a forwardly projecting bearing 43, in which is rotatably mounted a threaded shaft having a turn wheel 46. A vertical plate 47 has an upper collar 48 and a lower collar 49 on the guide rod 41, and similar collars (not shown) are in sliding engagement with the guide rod 42. The plate 47 also carries a nut 51 into which the threaded rod 44 extends, for vertically adjusting the plate 47 and the elements carried by it, as described below.

The plate 47 has joined to and extending from it a first inclined plate 52 and a second inclined plate 53, which plates are integrally joined at a juncture line 54 which extends horizontally above the conveyor.

The first plate 52 is provided with an aperture (not shown) through which extends the shaft 54 of an electric motor 56, which is secured to the first plate 52 by suitable bolts 58 which extend through the first plate 52 and into the motor 56. Similarly, the second plate 53 has an aperture therein through which extends the shaft 55 of a motor 57, motor 57 being secured to the second plate 53 by bolts 59.

On the shaft 54 of electric motor 56 is a rotary saw blade 61, while on the shaft 55 of the motor 57 is a rotary saw blade 62. The first and second plates 52 and 53 extend at substantially 90° to each other, being 45° to the horizontal. They consequently support the motors 56 and 57 with their axes and their shafts 54 and 55 in planes which are at right angles to each other, and as will be understood, the rotary saws 61 and 62 are similarly in planes which are substantially perpendicular to each other. The rotary saws 61 and 62 are so positioned that they cut a V-notch in a corrugated board being transported on the conveyor of the apparatus 10.

Referring now to FIG. 5, there is seen a corrugated board of the triple wall type, designated 80, and including three corrugated mediums 81, 82 and 83 between planar liners 84, 85, 86 and 87. When the corrugated board 80 is to be used as a box, it must be folded, and to effect this folding, a V-notch 90 is cut into it, so that there are thereby provided two portions of the corrugated board 80 separated by the notch 90, so that the two portions may be pivoted or rotated, relative to each other so that those two portions lie in substantially perpendicular planes. To provide the desired strength and rigidity, the material forming the two walls of the longitudinally extending notch 90 should be in substantial engagement when the corrugated board is folded to form a box or container, and for this reason, the walls of the notch 90 must be cut with some degree of preci-

sion. This is accomplished through use of the apparatus described in FIGS. 1-4 hereof.

The operation of the apparatus 10 begins with the positioning of each of the cutter assemblies, which includes the two rotary saws 61 and 62, their motors 56 and 57, the first and second plates 52 and 53 and the vertical plate 47. Each cutter assembly is positioned both horizontally and vertically. Thus, each of the cutter supports 30 on each of the bridges 25 and 26 is moved to the desired lateral or transverse position, depending upon the width of the corrugated board which is to be provided with the V-notches hereinabove described. The spacing between the various cutter assemblies will be determined by the positions at which the notches are desired in the corrugated board, which in turn is determined by the size of the front, back and side walls of the box which is to be made from the corrugated board. Thus, each of the cutter supports 30 is shifted laterally on each of the bridges 25, 26, and secured in the desired position. The vertical position of the rotary saws 61 and 62, relative to the conveyor belts 17, is established by manipulation of the turn wheel 46, to thereby raise or lower the vertical plate 47, the first and second plates 52 and 53, motors 56 and 57 and the rotary saws 61 and 62.

Corrugated board is placed on the conveyor belts 17 near the shaft 16, and is moved by the conveyor belts 17 towards the shaft 14, being held against the conveyor belts 17 by the hold down rollers 21 and 22. The corrugated board is then cut with a notch 90, as illustrated in FIG. 5, by each of the cutter assemblies, of which there are four as is clearly shown in FIG. 1. The lateral position and depth of cut of the rotary saws or cutters having been adjusted, the desired depth and position of the notch 90 is achieved, it being apparent that the set up time for a particular cutting job is minimal, and it further being appreciated that once a desired adjustment has been effected, the plural rotary saws of each assembly will be held firmly in the desired position, for effecting the desired degree of precision for cutting of the several notches 90.

In addition, it will be appreciated that the provision of the common support, including the plates 47, 52 and 53 for the two rotary saws 61 and 62 provides for adjustment of the two saws as a unit.

It will be appreciated that by the utilization of a plurality of small width belts 17, together with the rigidity of the triple wall corrugated board, the board is held sufficiently firmly during its passage along its path on the conveyor belts 17 that the desired position of cut is effected, while eliminating the use of anvils or back-up rollers beneath the cutter assemblies, thereby avoiding undue complexity of the machine.

It will be obvious to those skilled in the art that various changes may be made without departing from the spirit of the invention and therefore the invention is not limited to what is shown in the drawings and described in the specification but only as indicated in the appended claims.

I claim:

1. Apparatus for cutting V-notches in corrugated board comprising:
  - a. means for conveying planar corrugated board along a horizontal path,
  - b. a support above said conveying means,
  - c. cutter means comprising:
    - i. a pair of rotary cutters,

ii. a pair of shaft means for supporting and rotating said cutters in planes at substantially 90° to each other,

iii. motor means for driving said shaft means, and d. means carried by said support and supporting said cutter means comprising a pair of planar support elements independent of said motor means at substantially 90° to each other and at 45° to the horizontal, and each having a said shaft means extending therethrough, said planar support elements supporting said motor means.

2. The apparatus of claim 1, said conveying means comprising a plurality of individual conveyor belts, a pair of spaced, parallel shafts each having a plurality of pulleys thereon, each said conveyor belt being trained over a pulley on each shaft.

3. The apparatus of claim 1, said planar support elements being joined to each other.

4. The apparatus of claim 3, said motor means comprising a pair of motors, and means securing each said motor on a said support element.

5. The apparatus of claim 1, said motor means comprising a pair of motors, and means securing each said motor on a said support element.

6. The apparatus of claim 1, said planar support elements comprising first and second plates integral at a junction line.

7. The apparatus of claim 6, said motor means comprising a pair of motors, and means securing each said motor to a said plate.

8. The apparatus of claim 6, said last mentioned means further comprising a plate transverse to said path and said first and second plates and having said first and second plates secured thereto.

9. The apparatus of claim 8, and means for moving said plates and cutter means transverse to said path.

10. The apparatus of claim 1, and means for securing said cutter means in any of a plurality of selected positions on said support.

11. The apparatus of claim 10, and means for adjusting said cutter means transverse to said path.

12. The apparatus of claim 1, and means for adjusting said cutter means transverse to said path.

13. Apparatus for cutting V-notches in corrugated board comprising:

- a. means for conveying a planar corrugated board along a horizontal path,
- b. a support extending transversely above said conveying means,
- c. cutter means supporting means carried by said support and comprising first and second plates joined to each other at a junction line and joined to a third plate transverse thereto and to said path, said first and second plates being at substantially 90° to each other and at 45° to the horizontal,
- d. cutter means carried by said supporting means comprising a first shaft extending through said first plate and a second shaft extending through said second plate and being in planes at 90° to each other, a rotary cutter carried by each said shaft, and motor means for driving said shafts carried by said plates.

14. The apparatus of claim 13, and means for adjusting said cutter means transverse to said path.

15. The apparatus of claim 13, said motor means comprising a first motor secured to said first plate and

driving the first shaft and a second motor secured to the second plate and driving the second shaft.

16. The apparatus of claim 13, said conveying means comprising a plurality of individual conveyor belts, a

pair of spaced, parallel shafts each having a plurality of pulleys thereon, each said conveyor belt being trained over a pulley on each shaft.
